Louis E. Kupfer
By Arnold B. Shulick
ATTORNEY

UNITED STATES PATENT OFFICE

LOUIS EUGENE KUPFER, OF CHICAGO, ILLINOIS

TOY

Application filed February 24, 1932. Serial No. 594,799.

This invention relates to toys and more particularly to an animated toy.

One of the objects of this invention is to provide an animated toy adapted to be operated by the flow of heat waves.

Another object of the invention is to provide an animated figure in the act of sawing wood.

Other objects will appear in the course of the following specification and the accompanying drawing in which like reference characters indicate corresponding parts and in which:

Figure 1 is a perspective view of my device with parts broken away and shown in cross section, the saw being shown in forward position.

Figure 2 is a fragmentary view similar to Figure 1 with the saw shown in backward position.

In the drawing "1" indicates a supporting base plate having arranged centrally thereof an opening "2", the purpose of which will be presently explained.

Arranged centrally of the plate 1 is a saw buck as indicated at 3, which comprises a pair of X frames 4 and 5 having formed thereon supporting feet 6 attached to the base 1 in any suitable manner as shown at 7. Arranged between the frames 4 and 5 is a brace 8 attached thereto as shown at 9. A substantially cylindrical block 10 is supported in the upper V portions 11 of the buck 3, which is painted to simulate a log of wood, having a cut out portion 12, upon which is slidably arranged a saw 13.

A U-shaped guide member 14 having its end portions 15 and 16 bent at right angles thereto is arranged at right angles to the saw 13 and is attached to back face 17 thereof by soldering the end portions 15 and 16 thereto.

Arranged at one end of the base 1 is a standard 18 which in the present instance is indicated as an angle bar the bight portion of which is slit at the lower end thereof whereby the legs 19 and 20 may be bent backwardly to form supporting feet 21 attached to base 1 as shown at 22.

The end portion 16 has its extremity 23 ex-

tending beyond the end of the saw 3 and is slidably supported through the opening 24 in the leg 20.

Arranged at the other end of the base 1 is a manikin 25 in the present instance representing a man, which comprises a pair of L-shaped plates 26 attached to the base 1 as shown at 27. The plates 26 are spaced apart and have arranged therebetween at the lower portion thereof a reinforcing block 28. The plates 26 are shaped to simulate the contour of a man's body, legs and neck, the neck portions 29 of which are perforated to receive a cross pin 30. Attached to neck portions 29 in any suitable manner at the inner faces thereof are spaced guide blocks 31 having perforations in alignment with the perforations of the neck portions 29 and through which the pin 30 extends. Pivotally arranged on the pin 30 between the blocks 31 is a plate 32 having its upper end shaped to simulate the head 53 of a man, and the lower perforated end of which has connected thereto one end of an arm 33 as shown at 34 which in the present instance is formed as an extension of the saw 13.

A second arm 35 is attached to the plate 26 in any suitable manner, the hand portion 36 thereof being adapted to be supported upon an extension 37 of the frame 4 bent at right angles thereto.

The bight portion 38 of the guide 14 is slidably supported upon the upper edge 39 of a supporting plate 39 attached at its lower end to the side 40 of the base 1.

Rotatably mounted in an opening 41 in the base 1 is a shaft 42 which is rotatably supported in close proximity to its upper end by a bearing 43 formed at one end of an arm 44 attached at its other end as at 45 to a standard 46 having supporting feet 47 attached to the base 1 as shown at 48. Attached to the shaft 42 at its upper end is a propeller 49, the blades 50 of which are arranged in angular relation with respect to the base 1. The shaft 42 has an offset portion 51 formed therein in close proximity to its lower end, the bight portion 52 of which is arranged between the arms of the guide 14. The device is adapted to set upon a radiator

- or any other heating unit wherein the heat waves flow therefrom. The heat waves rising from the radiator pass through the opening 2 and engage the blades 50 of the propeller 49. The force of the waves against the blades 50 will act to rotate the propeller 49 and shaft 42, the bight portion 52 serving to impart a reciprocating movement to the guide 14 and saw 13 across the block 10.
- 10 The reciprocating movement of the saw 13 will rock the plate 32 on its pivot 31, thereby imparting a nodding movement to the head 53, the resulting movement giving an impression of a man sawing wood.
- 15 It is to be understood that other means may be used to impart movement to the propeller 49 than that described, and various changes may be made in the details of construction without departing from the spirit 20 of the invention or the spirit of the claims appended.

Having thus described my invention, what I claim is:

1. In a device of the class described comprising a perforated base, a saw-buck carried by said base, a log adapted to rest upon said saw-buck, a figure arranged at one end of said base and having a slot formed therein, a plate pivotally mounted in said slot, the 25 head of said figure formed on one end of said plate and the other end being perforated, one arm of said figure being pivotally connected to the perforated end of said plate, a saw, the hand of said arm adapted to grasp 30 the handle of said saw, said saw adapted to rest in operative position upon said log, a V shaped guide having the ends thereof bent in opposite directions and attached to said saw, an upright having a perforated end, one 35 end of said guide adapted to extend beyond one end of said saw and slidably carried by said upright, a supporting plate carried by said base and adapted to support the bight portion of said guide, a rod rotatably carried 40 by said base and having an eccentric formed intermediate the ends thereof and slidably arranged in said guide, a second upright having a supporting arm adapted to rotatably support the upper end of said rod, and a 45 propeller carried by the upper end of said rod.

2. A toy including a base member, a saw buck on the base, a log mounted upon the saw buck, having a cut out portion, a saw 55 movable through said cut out portion, a guide standard on the base having an aperture adjacent its upper end, a manikin on the base having a movable arm connected to one end of the saw, a U-shaped guide having its ends 60 attached to one side of the saw, one end of said guide extending beyond one end of the saw and slidably mounted in the aperture of the guide standard, a supporting plate attached to one side of the base with its upper edge 65 providing a supporting guide for the bight

portion of the U-shaped guide, and means operatively engaged with the U-shaped guide for imparting movement thereto and simultaneously impart a movement to the saw and the manikin.

In witness whereof I have hereunto set my hand this 14th day of October, A. D. 1931.

LOUIS EUGENE KUPFER.
